COLLAPSIBLE BOX

Philip J. Karam, Ottawa, Ontario, Canada

Application November 14, 1947, Serial No. 786,097

1 Claim. (Cl. 217—16)

1

The invention relates to improvements in a collapsible box, as described in the present specification and illustrated in the accompanying drawings that form a part of the same.

The invention consists essentially of the novel features of construction as pointed out broadly and specifically in the claim for novelty following a description containing an explanation in detail of an acceptable form of the invention.

The objects of the invention are to devise a collapsible box which may be easily and quickly collapsed or opened ready for use; to furnish a collapsible box in which the top and bottom may be removed without injury to any part of the container; to eliminate the use of nail pullers or hammers in opening boxes, shipping cases and the like; to fabricate a collapsible box which may be used many times; to construct collapsible boxes which may be used for containers, folding shelves, play pens and the like; to make a collapsible box which will be simple in construction and inexpensive to manufacture; and, generally, to provide a collapsible box which will be durable, dependable, and efficient for its many purposes.

In the drawings:

Figure 1 is a perspective view showing the collapsible box ready for use.

Figure 2 is a perspective view of the box showing the top partially removed.

Figure 3 is a perspective view showing the sides of the box in a partially collapsed position.

Figure 4 is a side view showing the sides of the box in a collapsed position.

Figure 5 is a transverse sectional view as taken on the line 5—5 in Figure 1.

Figure 6 is a sectional plan view, as taken on the line 6—6 in Figure 1.

Figure 7 is a perspective view showing the top or bottom wall of the box.

Like numerals of reference indicate corresponding parts in the various figures.

The collapsible box, as hereinafter described, may be made of plywood, wood, metal, cardboard and wood, or any other suitable material or combination of materials.

Referring to the drawings, the collapsible box consists of the side walls, as indicated by the numerals 10 and 11, and the end walls 12 and 13, which are each hingedly secured to one another. The top wall 14 and the bottom wall 15 of the collapsible box are adapted to be easily secured in position on the side and end walls 10, 11, 12 and 13, or removed therefrom.

The side walls 10 and 11 of the collapsible box

each consist of a panel 16 which has the corners of same notched so as to form a projection on each end thereof. The reinforcing strips 17 and 18 are suitably secured to the outer surface of each of the panels 16, and are in the form of a rectangle.

The end walls 12 and 13 of the collapsible box are each formed of a panel 19 which is higher than that of the side walls 10 and 11. These panels 19 are rectangular in shape and each have a pair of vertical slots 20 towards the outer ends thereof. The reinforcing strips 21 and 22 are fixedly secured to the outer surface of the panel 19 at the top and bottom thereof. The horizontal members 23 and 24 are fixedly secured to the upper and lower surfaces of the reinforcing strips 21 and 22, respectively. These horizontal members 23 and 24 abut the upper and lower edges of the panel 19 and each extend inward to form a flange or lip at the top and bottom of the latter.

The side walls 10 and 11 of the box are adapted to hingedly engage the end walls 12 and 13 so as to form the four walls of the box. In this respect, the projections 33 on each end of the panels 16 engage the slots 20 in the ends of the panels 19. The projections 33 on the panels 16 extend a predetermined distance through the slots 20 in the panels 19 and the vertical strips 25 and 26 are fixedly secured to the ends of these projections. In this respect, it will be seen that the projections on the panels 16 are free to hinge in the slots 20 in the panels 19, and that the vertical strips 25 and 26 retain the former in these slots, thus providing a hinged connection between the side walls and the end walls of the box.

The front vertical strip 25 on the left-hand end of the panel 16 of the side wall 10 is secured to the inner side of the panel; while the rear vertical strip 26 on the left-hand end of the panel 16 of the side wall 11 is secured to the outer side thereof. Furthermore, the front vertical strip 25 on the right-hand end of the panel 16 of the side wall 10 is secured to the outer side of the panel; while the rear vertical strip 26 on the right-hand end of the panel 16 of the side wall 11 is secured to the inner side thereof. The reinforcing strips 17 and 18 which form a rectangle on the panel 16 of the side wall 10 are located at the left-hand side thereof so as to leave a clearance between the former and the panel 19 of the end wall 13; while the reinforcing strips 17 and 18 on the panel 16 of the side wall 11 are located towards the right-hand side

of the same, thus leaving a clearance between these strips and the panel 19 of the end wall 12. The location of the reinforcing strips 17 and 18, and the vertical strips 25 and 26, permit the sides of the box to be folded so that the same will be flat when not in use.

The top wall 14 and the bottom wall 15 are interchangeable and adapted to be fitted between the reinforcing strips 17 on the side walls 10 and 11 and the flanges which are formed by the horizontal members 23 and 24, which abut the upper and lower edges of the panels 19.

The top and bottom walls 14 and 15 each consist of the panel 27 which is adapted to hinge or bend in the centre thereof. The panel 27 is reinforced by the frame portions 28 and 29, which are each U-shaped and abut one another to form a rectangle. The frame portion 29 has the sealing strips 30 and 31 fixedly secured thereto and the same extend over the frame 28.

The cleats 32 are secured on the inside of the panel 27 and suitably spaced apart so as to engage the side and end walls of the box when the covers are assembled thereon.

In the use of the invention, the side walls 10 and 11 and the end walls 12 and 13 are hinged open to form a rectangle. The bottom wall 15 is bent inward in a V-shaped manner and placed against the reinforcing strips 17 on the side walls 10 and 11. The bottom wall is then flattened and the ends thereof extend in past the horizontal members 23 and 24, which secure the same in position. The sealing strips 30 and 31 are nailed, or otherwise secured, to the frame portion 28 which prevents the panel 27 from bending, thus maintaining the same substantially in position with respect to the side and end walls of the collapsible box. The top wall 14 is similar to that of the bottom wall 15 and may be secured in position on the box in the same manner as hereinbefore described. In removing the top or bottom walls from the box, the sealing strips 30 and 31 are freed from the frame portion 28, thus permitting the panel 27 to be bent and removed therefrom in an opposite manner to that previously outlined in the assembly of the same.

In the foregoing, the box is described as having a front and back and also a top and bottom wall; however, it will be noted that these terms are employed for descriptive purposes only and that the box may be used in any position, with either the top or bottom wall serving as a cover.

What I claim is:

In a collapsible box, side walls each consist-

ing of a panel being notched at the corners thereof to form projections on each end thereof, reinforcing strips secured to the outer surface of each of said panels to form a rectangle, end walls each consisting of a panel higher than that of said side walls, the panels of said end walls being rectangular in shape and each having a pair of vertical slots therein towards the outer end thereof, reinforcing strips secured to the outer surface of said panel of said end walls at the top and bottom thereof, horizontal members fixedly secured to the upper and lower surfaces of said reinforcing strips on said end walls, said horizontal members abutting the upper and lower edges of said panels of said end walls and extending inward to form a lip at the top and bottom of the latter, the projections on the ends of said side walls engaging in the vertical slots in said end walls and extending therebeyond, vertical strips fixedly secured to the projection on the ends of said side walls to maintain the same hingedly secured to one another, top walls and bottom walls each consisting of a slightly flexible panel, a pair of U-shaped frame portions secured on the outer surface of each of said panels on said top and bottom walls, said U-shaped portions abutting one another to form a rectangle and permitting each of said panels of said top and bottom walls to bend along the centre thereof, sealing strips fixedly secured to one of said U-shaped frame portions on each of said top and bottom walls, said panels of said top and bottom walls being bent to facilitate the engagement of the ends thereof with the said end walls, and the free ends of said sealing strips being secured to the other of said U-shaped frame portions for substantially securing said panel of said top and bottom walls in a flat position.

PHILIP J. KARAM.
